UNITED STATES PATENT OFFICE.

CHRIS M. JORGENSEN, OF SEATTLE, WASHINGTON.

ANTICREEPING DEVICE FOR RAILS.

Specification of Letters Patent.

Patented Jan. 2, 1917.

1,210,943.

Application filed May 29, 1916. Serial No. 100,435.

To all whom it may concern:

Be it known that I, CHRIS M. JORGENSEN, a citizen of the United States, residing at Seattle, in the county of King and State of Washington, have invented certain new and useful Improvements in Anticreeping Devices for Rails, of which the following is a specification.

This invention relates to railway rail anchors which are employed to prevent longitudinal movements of track rails; and its object is the perfecting of devices of this character to render the same more efficient in use, more readily applied or disconnected, and less liable to become accidentally disengaged than are other rail-anchoring appliances known to me.

The invention consists in the novel construction, adaptation and combination of parts, as will be hereinafter described and claimed.

In the accompanying drawings, Figure 1 is an end elevation of my improved rail anchor applied to a rail which is shown in transverse section. Fig. 2 is a longitudinal section through 2—2 of Fig. 1. Fig. 3 is a horizontal sectional view of the device shown detached, said section being taken substantially on the broken line 3—3 of Fig. 30 2. Fig. 4 is a detached perspective view of a block element of the device.

The reference numeral 5 indicates a body having an arm 6 extending downwardly from one of its ends and may be manufactured by forging or otherwise. This body is provided at its top with a longitudinal slot which opens into a chamber 7, said slot being disposed to afford a relatively narrow flange 8 at one side and a wider flange 9 at the other side in order that, by tilting as indicated by broken lines α in Fig. 1, the device may be coupled with the flanges F of a track rail R. After being thus engaged, the device is moved into the upright position in which it is illustrated by full lines in the views, to introduce said rail flanges between the side wall 10 of said chamber and a shoulder 11 provided intermediate the width of the wide flange 9. The floor 12 of said chamber slopes, as shown in Fig. 2, with respect to the underside of the track rail.

13 represents a frame adapted to be inserted into the recess or chamber 7 from the rear end of the device and is provided with an aperture 14 to accommodate a transversely disposed roller 15, which is preferably fluted.

The body 5 is applied to a rail, as explained, and then advanced to have the arm 6 abut against a track-tie T. The frame 13 containing the roller is then introduced into the body chamber and on being forced forward will cause the roller to be wedged between the underside of the track-rail and the floor 12 of the device to thereby secure the same to the rail and in juxtaposition with the tie T.

To facilitate the engagement or disengagement of the roller with respect to the track-rail and the body, a tapering key may be advantageously utilized, for which end 70 slots 16 are provided in the side walls of the body and a transverse slot 17 provided in said frame.

To advance the roller, the referred to key is inserted, as indicated by broken lines 18^a 75 in Fig. 3, through the slots of the body and frame and when driven in will act against slot faces 16¹ and 17¹ to effect the setting forward of the frame and roller which is carried thereby.

To retract the roller, the key is driven into the device, as indicated by broken lines 18^b in the view, through the body slots 16 and against the ends 16² thereof and the advance end 13¹ of the frame. 80

The front surface 6¹ of the arm 6 is arranged in such angular relation to the under surfaces of the body flanges 8 and 9 that when the latter are seated on the rail flanges F and the arm 6 is brought against the tie T, 90 there will be a space between the tie and the upper portion of the arm and the body. The roller 15 is, moreover, intended to operate in the rear end of the chamber to engage the rail to the body at the rear end 95 of the latter while the arm 6 is juxtaposed with the tie at its lower portion only.

13² represents a tooth depending from the frame 13 and engageable in any of the transverse grooves 20 provided in the floor 12 of 10 the body 5 to prevent any accidental rear movement of the frame in the event of the roll becoming temporarily loose.

The device thus being engaged at its ends will, upon being subjected to any strains, 10 have a tendency to bend and be less liable to break or become displaced when the force is excessive. Because of the converging surfaces of the rail and body against which the roller acts, any forward creeping of the rail 11 is obviated when the anchor is placed against the rear side of a tie!

Should the track be utilized for traffic in both directions, then the anchor should be used on both sides of a tie, as would also be the case on certain inclined ways or 5 grades.

What I claim is—

1. In a device of the class described, a rail-clamping means comprising a chambered body, said body having at its top a 10 longitudinal groove communicating with the referred to chamber and disposed to provide two inwardly directed flanges at opposite sides of the groove whereby the body may be suspended from the flanges of a track rail, 15 and means insertible within the body chamber from one end of the body and below the rail for securing said body to the rail and also serving to hold said body in juxtaposition with a track tie.
2. In a device of the class described, a rail-clamping means comprising a chambered body provided with an arm depending from one end thereof, said body having at its top a longitudinal groove communicating with the referred to chamber and disposed to provide two inwardly directed flanges of unequal widths at opposite sides of the groove whereby the body may, by 25 being tilted, be engaged with the flanges of a track-rail, and means insertible within the body chamber and below the rail for securing said body to the rail.
3. In a device of the class described, a rail-clamping means comprising a body 30 adapted to be suspended from the flanges of a track-rail and having an arm depending from one end of said body, said body being provided with a recess having a floor inclined from the plane of the underside of 35 said rail, and a roller adapted to mutually engage against the underside of said rail 40

and the aforesaid floor to couple said body to the rail and also serve to maintain the body in position to cause the arm thereof to bear against a track tie.

4. In a device of the class described, a rail-clamping means comprising a body adapted to embrace the flanges of a track-rail and having an arm depending from one end of said body to bear against a track 45 tie, said body being provided with a recess having a floor inclined from the plane of the underside of said rail, a roller adapted to mutually engage against the underside of said rail and the aforesaid floor to 50 couple said body to the rail, and an apertured block serving as a frame for said roller and insertible therewith in the block recess to maintain the axis of the roller in 55 rectangular relation to the rail.

5. In a device of the class described, a one-part body provided with means integral therewith for detachably suspending the same from the flanges of a track-rail, 60 said body being chambered to provide a recess subjacent to said rail flanges and with a floor disposed in angular relation to such flanges, a roller, and means provided with a recess to accommodate said roller and adapted to be inserted therewith in said 65 recess to maintain the axis of the roller in transverse relation to the rail for coupling said body to the rail, said frame also serving to enable the roller to be readily removed from said recess for disengaging 70 said body.

Signed at Seattle, Washington, this 9th day of May, 1916.

CHRIS M. JORGENSEN.
